[57] **CLAIM**

The ornamental design for a portion of a decorative mounting plate for electrical communications connections, as shown.

DESCRIPTION

FIG. 1 is a front elevational view of one embodiment of a portion of a decorative mounting plate for electrical communications connections showing my new design;

FIG. 2 is a front elevational view of the decorative mounting plate of FIG. 1 mounted in a conventional two-gang face plate, including a conventional two-plug electrical outlet;

FIG. 3 is a front elevational view of a further embodiment of a portion of a decorative mounting plate for electrical communications connections showing my new design, this embodiment being a unibody faceplate including a one-gang opening therein;

FIG. 4 is a front elevational view of another embodiment of a portion of a decorative mounting plate for electrical communications connections showing my new design, this embodiment being a unibody face plate; and,

FIG. 5 is a front elevational view of the decorative mounting plate of FIG. 1 mounted in a conventional single-gang face plate.

The elements shown in broken lines on the drawing figures form no part of the claimed design.
